UNITED STATES PATENT OFFICE.

HANS CHARLES BEHR, OF SCARSDALE, NEW YORK.

PROCESS OF AND APPARATUS FOR CRUSHING ORE.

1,127,853.

Specification of Letters Patent.

Patented Feb. 9, 1915.

Application filed April 10, 1914. Serial No. 330,951.

To all whom it may concern:

Be it known that I, HANS CHARLES BEHR, a citizen of the United States, residing at Scarsdale, in the State of New York, have 5 invented certain new and useful Improvements in Processes of and Apparatus for Crushing Ore; and I do hereby declare the following to be a full, clear, and exact description of the invention, such as will enable others skilled in the art to which it 10 pertains to make and use the same.

The present invention relates to a process of and an apparatus for crushing rock, and has for its objects: 1. To provide a means 15 for striking the blow at a higher velocity than heretofore admissible with present devices using elastic fluids under high pressures. 2. To reduce the unavoidable shocks on the more delicate parts of the machine 20 that are incident to such high speed operations. 3. To provide a method for carrying out such operations with a greater economy in power consumption, notwithstanding the 25 variations in the extent of the lower end of the piston. 4. To provide a machine of comparatively small weight for a given energy of blow, thereby not only reducing the 30 cost of the machine, but also enabling the more ready handling of the parts in making adjustments necessary in operating the machine.

With these and other objects in view the invention consists in the novel combinations of parts, details of construction, and relations of steps constituting my process all as 35 will be more fully hereinafter disclosed and particularly pointed out in the claims.

Referring to the accompanying drawings forming a part of this specification in which like letters and numerals designate like parts in all the views:—Figure 1 is a diagrammatic longitudinal sectional view of a rock stamp and its associated mechanisms built in accordance with my invention; Fig. 40 2 represents an indicator diagram for the short stroke of my power piston; and Fig. 3 45 represents an indicator diagram for the long stroke of said piston.

In order that my invention may be the more clearly understood it is said:—Experiments which I made have convinced me that in order to crush rock most efficiently and make it most suitable for subsequent

treatment by certain industrial processes, the blow of the stamp head must take place 55 with the maximum velocity admissible with safety to the apparatus. Existing steam- and pneumatic stamps are, on account of the power systems by which they are operated and which power systems are subject to the 60 usual pressure limitations, necessarily provided with very large pistons. These large pistons are through their rods usually coupled to the stamp head proper by some elastic connection, thus relieving them partly of 65 the shock incident to the work of crushing by bringing them to rest more gradually than would otherwise be the case. But even with such devices striking velocities like those I employ would not be admissible with 70 pistons of the size now in use. Another advantage in favor of light pistons is, that while power is expended proportionally to weight in putting energy of motion into the piston as well as into the stamp head, owing 75 to the necessary elastic connection between the piston and stamp head practically only the energy of the stamp head itself can be utilized in crushing rock. Therefore the lighter the piston and rod as compared with 80 the total mass accelerated, the more economically the power operating the machine will be utilized. In order to simplify the following description pressures shall be understood, except where otherwise stated, to 85 mean total absolute pressures: *i. e.*, pressures per square inch reckoned from zero pressure multiplied by effective area of the piston. Thus, if there is a piston rod to be reckoned with, deduct the area of said rod from the 90 full area of the piston to obtain the effective area. For simplicity also the stamp will be considered as if it were not affected by gravitation. Since the point at which the piston completes its downward stroke is 95 during its regular operation not always the same, due to variations in thickness of the layer of rock on the die and to the moderate wear of the shoe and the die that is permitted before adjustments are undertaken to 100 correct for such wear, and since also it is necessary to provide against the piston striking the lower cylinder head when the rock feed happens to stop, the distance between the lower cylinder head and the under 105 side of the piston when the latter has com-

pleted an average stroke must be considerable. The return of the stamp on its upward stroke, however is attended with a waste of power, when as at present, the operating fluid is ordinarily admitted to and then exhausted at a lower pressure from such a large clearance space. To avoid these serious objections, my present invention among other things provides a means 10 for permitting the up and down strokes to take place without admissions or exhausts of counter pressure air through valved openings, and further provides a large volume of compressed air in continuous communication 15 with the space beneath the piston. The down stroke is thus accomplished by a higher pressure acting on the upper face of the piston than beneath it, while the up stroke takes place by permitting an exhaust 20 from above the piston at a pressure lower than that acting beneath it. For the sake of brevity in the following disclosure the pressure acting beneath the piston will be called the counter pressure, and the air supplied 25 to and exhausted from the space above the piston will be called the operating air. A high average pressure per square inch above the piston in excess of the counter pressure below it is obviously necessary with a piston 30 of small size, in order that the stamp head may reach the desired high striking velocity. But to use with economy the ordinary systems of steam or compressed air transmission with an exhaust at atmospheric pressure 35 or below, would require initial pressures much in excess of those found practicable. If a high exhaust pressure could in fact be used, then the required ratio of expansion would also be lower and the initial pressure 40 would be less in excess of the average pressure needed to give the stamp the desired speed. But to secure economy of power in such cases the exhausted steam or air should then be entirely utilized in driving other 45 machinery operating coincidently with the stamp, a method rarely practicable. In the case of compressed air, on the other hand, the exhausted air might be utilized in a motor arranged to assist in driving the compressor 50 which provides the compressed air for operating the stamp. But it will be much simpler and more economical to divert the exhausted air to the suction of the compressor as in the present invention, thereby 55 securing a low rate of compression with reduction of compression temperatures and of the losses pertaining to such temperatures. This last case in fact represents a closed 60 system of compressed air power transmission with high pressure both on supply and return, operating through suitable valves between the stamp cylinder and compressor. The application of such a system, in connection with a continuously acting high pressure, operating without valves, and forming 65

a separated closed system for the space beneath the piston, constitutes the first and main idea of my invention. Since, as pointed out, the length of the piston stroke will in operation vary with the thickness of rock 70 between the shoe and die, and with the permissible amount of wear between adjustments, the ratio of expansion of the air driving the piston downward must be such that for the longest stroke allowed the final pressure after expansion will not fall too much 75 below the counter pressure acting beneath the piston. In other words a great excess of counter pressure before completion of the down stroke would cause the stamp head to 80 lose too much velocity and therefore in force of impact, which latter it is one of the main objects of this invention to maintain. The work done on the up stroke by the excess of counter pressure over exhaust pressure is 85 imparted to the mass of the stamp as energy of motion, and this energy, through closing of the exhaust at the proper point of the stroke, is transferred from the stamp to the air above the piston, first by compression of said air to about admission pressure, and thereafter by forcing part of the air 90 so compressed into the admission valve chamber and the spaces connected therewith. The work thus transferred to the air is obviously again available to assist driving the stamp on its next down stroke. The unavoidable variation in the length of the stamp stroke will obviously cause the energy 95 of motion acquired by the stamp on its up stroke to be greater for a long stroke than for a short stroke, and hence more work will be taken up by the air above the piston after closure of the exhaust in the former case 100 than in the latter. Since the work of compression will always be the same, the difference will be in the displacement of the amount of air into the admission chamber, so that for the long stroke the piston will 105 approach closer to the upper cylinder head than in the case of the short stroke. It thus will be clear that with the manner of operation described a considerable clearance space above the piston will not affect the economy. Ample clearance may therefore be provided 110 to safeguard against the piston's striking the cylinder head in case of air leaks past the piston, or derangement of the mechanism causing an up stroke of unusual energy. 115

Referring to the drawings: A represents the stamping machine proper, B a reservoir of high pressure air, communicating with the upper end of the stamp cylinder 1 by means of the pipe 2. The lower pressure air 120 exhausted from the upper end of cylinder 1 is conveyed through pipe 3 to the exhaust storage reservoir C.

D is a reservoir of counter pressure air, in free communication with the lower end of 130

the stamp cylinder 1; while at E is shown a compressor adapted to draw air from the exhaust reservoir C to compress it to the admission pressure, and to force it into the 5 high pressure reservoir B, as will be more fully explained hereinafter. The small compressor shown at F is used for making up the air lost from the system by leakage and for this purpose it is adapted to draw 10 air from the atmosphere and compress it to the exhaust pressure existing in C, as will likewise appear hereinafter.

Referring to the stamping machine proper, the mortar box 4 has fitted in its 15 base the die 5. The feed opening for the rock is at 6 on one side of said box and the discharge opening 7 with the screen 8 is located on the opposite side. The chute 9 conveys the rock to be crushed to the feed opening 6. The stamp head 10 of the stamping machine A has at its lower end the shoe 11 said shoe being secured with its dovetail lug 12 by means of the key 13 to a recess in said head as shown. The upper end of the head 20 is provided with a screw thread 14, over which is screwed the cap 15. The piston rod 16 passes through an opening 17 in the top of cap 15, and is formed at its lower end with the disk 18, which latter is thus 25 closed in the space between the top of the stamp head 10 and the cap 15. Above and below disk 18, are provided elastic cushions 19 and 20 which may be of rubber or compressed air, forming an elastic connection 30 between the stamp head 10 and the piston rod 16. At the upper end of rod 16 is secured the piston 21. The upper end of the stamp head 10 with its cap 15 is guided vertically in the bored guide 22, which is 35 supported on the pedestal frame 23, and has at its upper end the extensions 24, 24, by which it is joined to the lower head of the stamp cylinder 1.

In order to provide for the vertical adjustment of the stamp cylinder 1, so as to allow 40 for the gradually lowering position of piston 21, due to the wear of the die 5 and shoe 11, there is placed between the flange 26 on guide 22 and the corresponding flange 27 on the pedestal 23, a plate 28 of a certain thickness when the die 5 and shoe 11 are new. This plate is then replaced by a thinner one 45 when the die and shoe become worn a certain amount, and as the wear proceeds still thinner plates 28 are inserted, so that the lower surface of shoe 11 will always be permitted, notwithstanding the wearing away of the parts, to work substantially at a maximum of efficiency. Other methods of 50 adjustment may obviously be used, the one here described serves to illustrate one example of such adjustment.

The pipes 2 and 3 connecting the stamp cylinder 1 with the reservoirs B and C are 55 preferably provided with flexible sections

such as 29 and 30, so as to permit of the said vertical adjustment of the cylinder 1 referred to. The counter pressure air reservoir D is shown as rigidly connected to cylinder 1 by the short pipes 31 forming part 70 of the free communication between reservoir D and the space beneath piston 21. For the purpose of making up air losses and for filling with air at the start the small pipe connection 77, 77 communicates between 75 reservoir D and the high pressure pipe 2 at a point 32 between cylinder 1 and the flexible connection 29. At 78 I provide a reducing valve in the pipe 77 for limiting the 80 pressure in reservoir D.

In the lower part of the stamp cylinder barrel 1 there are a number of openings 33, 33, affording a free communication with the annular chamber 34, connected through pipe 31 with the counter pressure reservoir D 85 and causing the pressure existing in reservoir D to act continuously on the under side of piston 21 as long as the latter remains above the circle of openings 33, 33. These openings are located at such a height in relation to the piston travel, that if during the 90 operation of the stamp head 10 the feed of rock to the mortar 4 should fail, so that there would be no layer of rock on the die 5 to take up the energy stored in the descending 95 stamp, or if the shoe 11 should break, then the piston 21, in passing the said openings 33, 33 will automatically close off communication of the space 35 beneath it, with reservoir D, and cause the moving mass of stamp 100 and piston to spend a large part of its energy of motion in compressing the air, thus trapped or imprisoned beneath the said piston 21. The effect of thus automatically trapping the air will be to materially reduce 105 the force of the blow which would otherwise fall on parts of the machine, which are not as yielding as the bed of rock. The reason for having a number of openings 33, 33 is to provide area as large as possible and of a 110 minimum height for the unobstructed flow back and forth of the counter pressing air, while at the same time to retain a metal surface at frequent intervals around the circumference of the cylinder to properly guide 115 the piston 21 as it passes over the openings 33, 33.

In Fig. 1 the stamp 10 with its piston 21 is shown at the lower end of the stroke and the rock on the die having just been crushed has 120 absorbed the full energy of the stamp blow. The upward or return stroke begins as soon as the pressure above piston 21 is sufficiently reduced by the opening of exhaust valve 36, located in the lateral chamber 37 125 near the upper end of cylinder 1, and controlling communication with exhaust reservoir C through chamber 50 and pipe 3. In Fig. 1 valve 36 is shown in its closed position, being held to its seat by the spring 38. 130

The chamber 37 opens into cylinder 1 at port 39, which is given a very much less area than the aggregate of the ports or openings 33, 38, because the final piston speed on the up stroke *i. e.* during the exhaust, is much less than the velocity acquired during the down stroke, and therefore a less area for port 39 suffices. The beginning of the exhaust by the opening of valve 36 is controlled 5 independently of the movement of the stamp head 10 and takes place at such periods that the stamp head 10 may, without material retardation, complete its longest permissible stroke. The opening of the said valve 36 10 as will now be explained is preferably accomplished by a small electric, or air motor, as shown at 40 mounted on the bracket 41 at the side of guide 22. Motor 40 drives by pulley 42 through belt 43 the pulley 44 15 mounted on cam shaft 45, which latter is carried in bearing bracket 46 and has mounted on it the cam 47. Cam 47 works against a vertical lever 48, fixed on the outer end of a shaft 49, which passes airtight through the side wall of chamber 50, located below valve 36 and connected by pipe 3 to reservoir C as shown. Inside of chamber 50 there is mounted on the shaft 49 a horizontal lever 51, which bears against the lower end of the stem 52 of valve 36. As cam 47 revolves it oscillates lever 48, thereby elevating inside said chamber 50 the lever 51 and thus lifting valve 36 against the pressure of spring 38. The closing of valve 36 takes place 20 when lever 48 is released by cam 47, and said closing is so timed, that it takes place as soon as possible after the piston 21 on its upward stroke has passed and thereby closed the exhaust port 39. The effect of the arrangement described is: The exhaust is 25 opened at the proper moment independently of the movement of the piston 21, the closure of the exhaust takes place during the regular operation dependent only on the distance of the piston from the upper cylinder head as it approaches the latter and independently of the separate later closure of the exhaust valve 36. These features are important to the proper operation of the stamp. 30 The piston might of course be so arranged as to act on the exhaust valve and close it by means of a mechanical connection, instead of by the simpler and more positive expedient of having the piston act as a valve itself. But such less reliable means would only carry out the same idea of closing the independently opened exhaust by the upward movement of the piston. The port 39 is located at such a distance below the upper 35 cylinder head, that during the normal operation of the piston, the work stored in the upward movement mass of stamp and piston will, after the latter has closed the said port 39, be spent in doing useful work on the air 40 imprisoned above it. This work will consist

at first in compressing the air to about the admission pressure, thereby opening the admission valve 54, located in valve chamber 55 in the upper cylinder head 53, and thereafter in displacing air of admission pressure past valve 54 into chamber 55 and reservoir B, connected to said chamber 55 by pipe 2. After the energy of the upwardly moving stamp has been thus spent there must still remain as a safety precaution some distance between the top of the piston and the underside of the cylinder head. When the piston is at or near the upper end of its stroke it is obvious that communication with reservoir C and the pipe system under its pressure must be closed, for otherwise the counter pressure air in cylinder 1 would rush from the space beneath the piston into said pipe system. This is prevented by making the piston 21 sufficiently deep, so that its lower edge, when in its highest position, does not uncover port 39; or it may also prevent the same, by so timing the parts that exhaust valve 36 will have been closed by its operating connections before piston 21 reaches a position where its lower edge uncovers port 39. Exhaust valve 36 must, however be closed in any event before the upper edge of piston 21 on its downward stroke uncovers port 39, so that air under admission pressure may not rush into the said pipe system or the exhaust space 50. 45

The admission valve 54 is formed with its upper part 56 as a piston capable of sliding airtight in a vertical direction in the bore 57, the upper part of which bore forms a chamber above said part 56. The spring 58 holds valve 54 to its seat 59. A duct 60 leads from bore 57 laterally and then down through the wall of cylinder 1, where it issues into the interior of said cylinder at the small ports 61 and 62. The lower of these ports 62, is located at such a height, that the lower edge of piston 21 will have passed and uncovered it on its upward stroke before the upper edge of the piston has closed off exhaust port 39 as is indicated in dotted lines Fig. 1. Counter pressure air from reservoir D in this position accordingly acts through duct 60 on the upper face of valve piston 56 to maintain the same closed before the exhaust port 39 is closed. The pressure thus acting is reinforced by that due to spring 58, the strength of which is so proportioned as to cause the compression of the air imprisoned, as piston 21 rises, to reach about the admission pressure, before the admission valve 54 will be lifted off its seat by the pressure of such imprisoned air acting on that part of the area of valve 54 exposed by the valve opening 63. As soon as valve 54 however has been thus opened by compression of the air beneath it, its entire lower surface will be exposed to the admission pressure from

reservoir B, so that it will now be held open by the greater force acting beneath it. With valve 54 being thus held open, the down stroke of piston 21 proceeds under full admission pressure through port 63 until the upper edge of piston 21 has passed port 61, when air of admission pressure is allowed to pass up duct 60 into chamber 57, where it acts on the upper face of valve piston 56. The pressures above and below valve 54 will now be balanced, and the latter is at once closed by spring 58. Port 61 is located at such a distance from the cylinder head 53, that valve 54 will close at the desired predetermined point of the piston's down stroke, said port 61 being sufficiently higher than such point as to allow for a slight delay in the closure of the valve 54 due to resistance and inertia. The remainder of the stroke of piston 21 is thereafter accomplished under the expansive force of the air above it.

When it is required to start the machine in operation the stamp head 10 and piston 21 should be at the lower end of their stroke as indicated in Fig. 1, thereby securing the full energy of the up stroke to insure the compression necessary for opening the admission valve 54. To enable one to bring the piston from any other position to the lower end of its stroke, air of admission pressure may be permitted to enter the space above the piston through the small opening 64 in cylinder head 53 by lifting the valve 65 by means of a hand lever 66, fulcrumed at 67 to a lug 68 on valve chamber cover 69, and engaging with its short arm 70 the collar 71 at the upper end of the stem 72 of valve 65. As stated above, air of admission pressure is supplied on the down stroke from reservoir B to the space above piston 21 and afterward on the up stroke exhausted from said space to the exhaust reservoir C. The pressure in these two reservoirs is maintained by the compressor E, which draws air from reservoir C on its suction stroke through pipe 73, compresses it to admission pressure and delivers it through pipe 74 into reservoir B. The spring loaded relief valve 75 is provided to permit the escape of air from reservoir B into reservoir C in case of over pressure in said reservoir B, which would occur if case the stamp were stopped and compressor E kept running. As a further precaution a relief valve to the atmosphere from reservoir B is provided at 76.

The counter pressure reservoir D is supplied, for filling and for making up for leakage, from reservoir B through the small pipe 77, 77, and reducing valve 78, which latter prevents air from entering reservoir D unless the pressure in said reservoir is below that required for the counter pressure. A relief valve to the atmosphere from reservoir

D is shown at 79 to prevent any accidental accumulation of pressure therein. Instead of discharging to the atmosphere at 79 the waste air from reservoir D may also be so piped as to deliver into the exhaust reservoir C.

In order to make up for the unavoidable leakage in the stamp cylinder pipes and reservoirs there is provided a small compressor F, which may be connected to and driven with compressor E as shown. Compressor F draws air from the atmosphere through suction valve 80, and after compressing it to the exhaust pressure existing in reservoir C, forces it past outlet valve 81 through pipe 82 into the exhaust pressure side of the system.

For filling the system with the various pressures previous to starting the machine in operation, air of the exhaust pressure required is supplied from any suitable source to the exhaust side through the pipe 83, and the valve 84, which is ordinarily closed. At the same time the main compressor E is kept running to compress the air so supplied to admission pressure and to deliver it into reservoir B, from which reservoir part of it flows to reservoir D until the counter pressure therein required, as fixed by adjustment of reducing valve 78, is reached. At 85 and 86 are stop valves to shut off the admission and exhaust pipes from the stamp cylinder 1.

In Figs. 2 and 3 are shown indicator diagrams of the total pressures and cylinder volumes at various periods of the strokes of the piston 21. In said diagrams the vertical lines represent total pressure (i. e. pressures per square inch multiplied by the effective areas in square inches), while the horizontal lines represent volumes of displacement or distances of piston travel under said total pressures. In these diagrams the corresponding points are indicated by the same numeral, and the effect of the weight of the stamp head is not specially indicated, said weight being treated in said diagrams as a constant, or as a part of the pressures acting during the up and down strokes of the piston. In each Fig. 2 and 3, the point of intersection 100 of the lines 1000 and 1010 indicates the beginning of the cylinder volumes and the zero of the total pressures. The distance between lines 1000 and 1100 represents the pressure of the atmosphere, and the length of the line 1110 Fig. 2 represents the length of the shortest piston stroke, such as is had when the shoe 11 and die 5 are new, as explained above.

Considering Fig. 2, and a short piston stroke, the top of the piston will at the beginning of its down stroke be at point 115, and the cylinder space corresponding to the line 1150 or the distance between line 1010 and point 115, between the piston and cyl-

inder head, will be filled with air of the absolute admission pressure indicated by the vertical distance represented by line 1010 or between the points 100 and 101. The said air having been compressed to this admission pressure by the energy of motion of the preceding up stroke of the stamp head and piston and the admission port being open, also through the same action of the piston, the down stroke proceeds under full admission pressure until the admission valve closes at that period of the down stroke corresponding to the point 102, the distance traveled or volume swept by the piston being represented by the distance from point 115 to point 102. From now on the down stroke proceeds under the expansion of the air to the end of the piston stroke represented at point 113. The final pressure represented by the distance between line 1000 and point 113 exceeds the counter pressure represented by the distance between line 1000 and point 112 by an amount measured by the distance between points 112 and 113, and exceeds the exhaust pressure represented by line 1050 by an amount measured by the distance between points 113, and 114. The triangular area indicated by points 113, 104 and 114 represents the theoretically irrecoverable loss of energy by limiting the stroke to the point 112. In the case of the longest stroke explained in the diagram Fig. 3 the stroke, which is measured by the distance between points 116 and 117, or by line 1160 starts at point 120, the piston being nearer to the cylinder head than in the case of the short stroke, as indicated by the length of line 1200, being less than the length of line 1150 in Fig. 2. Expansion begins at the same point 102 from the cylinder head as in the case of the short stroke, but as the stroke is much longer, terminating at 117, the pressure now drops below the counter pressure indicated by line 1090 by an amount measured by the distance between the points 117 and 119 so that the stamp is being slightly retarded by a gradually increasing excess of counter pressure. The energy thus taken from the stamp is, however slight, being measured by the area indicated by the points 103, 117, and 119. A further slight irrecoverable loss is measured by the area indicated by the points 119, 104 and 118. The losses indicated, aside from friction and losses due to temperature fall, are those theoretically irrecoverable. When comparing the small areas representing them with that representing the total work, it appears that they can be kept very small by suitable choice of operating pressures. The exhaust having been opened about the time of completion of the down stroke, by the separate motor referred to, exhaust takes place from above the piston at the

pressure indicated by line 1050 being less than the counter pressure indicated by line 1090 extending between points 103 and 109 by the amount indicated by the distance between points 103 and 121, by which excess of pressure the piston is impelled upward until it closes off the exhaust at point 105. At the point 106 the pressures above and below the piston have become equalized and the mass of stamp and piston have acquired their full energy of motion. From now on the energy so gained is again spent in doing work on the air imprisoned above the piston. The first part of this work will consist in compressing the imprisoned air from the pressure at point 106, now equal to the counter pressure indicated by the distance between points 103 and 109 or by line 1090 to about admission pressure indicated by line 1010, thereby forcing open the admission valve 54, Fig. 1 as previously explained. The remaining energy of the upwardly moving stamp is spent in forcing air at admission pressure past the admission valve into the valve chamber 55 and the reservoir 90. B. The total compression and displacement work thus performed on the air is represented, in the case of the short stroke, Fig. 2, by the area 106, 107, 115, and 111, theoretically equal to area 112, 114, 105, and 106. Similarly the long stroke area 106, 107, 120, and 116, in Fig. 3 is equal to area 117, 118, 105, and 106. For the long stroke the piston and stamp will, on account of the longer distance over which the excess counter pressure acts, obviously gain more energy of motion than for the short stroke, so that after the work of compression is completed at 107, there is also a greater amount of energy remaining in the mass of the stamp, which energy must be absorbed in forcing a larger volume of air against admission pressure, and since this pressure is constant, the distance required to take up the greater work must be longer, as indicated by the distance 107, 120 being greater than the distance 107, 115 for the short stroke. The diagram of the compressor E will be the same for both the long and the short strokes. If there were no resistance or temperature losses its amount would be represented by the area of the diagram 104, 102, 107, and 105. In other words this area represents that part of the compressor work which is carried in the form of compressed air to the stamp cylinder after deducting all losses of compression and transmission of said air. By placing the compressor as close to the stamping machine as possible the heat losses in transmission can be kept small by suitably covering the pipes. Effective heat insulation is here favored by the small temperature range due to the moderate compression ratio of the closed system.

It will be clear from the preceding de-

scription that in recompressing the air required for the operation of the stamp from exhaust pressure to admission pressure, the compressor E is aided by the work of the 5 piston during the latter part of its upstroke, the energy for which work the piston and stamp head obtained from the excess of counter pressure over exhaust pressure acting during the early longer part of the up 10 stroke.

The operation of my improved stamp will be clear from the foregoing but may be briefly summarized as follows: The stamp head 10 is first brought into the position 15 shown in Fig. 1, as by closing the valve 36, admitting counter pressure from reservoir D into cylinder 1 under piston 21, and then opening by hand valve 65 to admit into cylinder 1 above said piston admission pressure from reservoir B. If the parts are not 20 suitably adjusted, the shoe 11 can be raised or lowered by jacking up the cylinder 1 and inserting strips 28 between the flanges 26 and 27 to bring the lower surface of shoe 25 11 at the desired distance above die 5. The flexible connections 29 and 30 in pipes 2 and 3 permit said pipes to give under such 30 adjustments. Said adjustments are also made to compensate for wear on the shoe 11 and 35 die 5. But as this wear is not compensated for until it has reached a predetermined degree, the said shoe will make short and long strokes as above explained and the energy characteristics of these strokes are 40 indicated in the diagrams of Figs. 2 and 3. It is desirable to provide a considerable space in the cylinder 1 below the ports 33 as 45 illustrated, in order that the air may be trapped in said space and cushion any abnormal down strokes of piston 21. On the upstroke of said piston it automatically 50 closes the exhaust port 39 and traps air between its upper surface and the cylinder head 53, thereby compressing it to admission 55 pressure. The energy stored in this air is later returned to the system as above explained, and while said air is being thus compressed, the valve 54 is held to its seat not only by the spring 58, but by the 60 pressure of the air from counter pressure reservoir D, which passes through channel 60 to the top of valve 54. As the piston 21 continues to rise, however, the compression of the air thus trapped will reach such a 65 point that valve 54 will open thus permitting pressure from reservoir B to counter balance that on the top of valve 54. The piston will now descend under full admission pressure from reservoir B until it 70 passes and uncovers the ports 61 to admission pressure from reservoir B. When said port 61 is thus uncovered, air at admission pressure passes up channel 60, balances the pressure on the lower face of valve 54 and permits spring 57 to close said valve, where-

upon the piston 21 proceeds on its down stroke under the expansive force of the air and under the action of gravity.

The exhaust valve 36 is operated independently of the piston 21 by means of the 70 motor 40 and its connections. The counter pressure reservoir D supplies air at a less pressure than that in reservoir B, to lift the piston, and this air is not permitted to escape past the valve 36 out of the cylinder 75 1. It forms a sort of cushion or counter pressure sufficiently powerful to restore the parts while not preventing the attainment of high downward velocities on striking. Since this counter pressure air is not exhausted 80 from the system the energy losses heretofore experienced in returning the parts are obviated by my invention. In other words, it will now be clear that my present system provides a large volume of compressed air in reservoir D always in communication with the lower surface of the piston, that the down stroke is accomplished by a higher pressure from reservoir B on the upper surface of said piston, and that 85 the piston 21 is returned by providing an exhaust of the air above the piston into reservoir C at a lower pressure than exists in reservoir D. It will further now be clear that by my process of providing this intermediate counter pressure in reservoir D, and diverting the exhaust air of reservoir C to 90 the suction side of a compressor which returns said air at admission pressure to reservoir B, that a maximum of energy in the exhausted air is saved to the system, so that I 95 avoid the heavy losses experienced in the old systems. I further by this process secure a low rate of compression and a reduction of compression temperatures and of 100 the losses pertaining to such temperatures. In fact it will now be clear that my mechanism constitutes a closed system with high 105 pressure both on supply and return, acting through a compressor, coupled with an intermediate closed counter pressure system, there being no energy lost through exhausts to the atmosphere.

It is obvious that those skilled in the art 110 may vary the details of construction as well as the arrangement of parts without departing from the spirit of my invention and therefore I do not wish to be limited to the above disclosure except as may be required by the claims.

What I claim is:

1. In a stamping machine the combination of a reservoir for containing air at admission pressure; a reservoir for containing air at exhaust pressure; a counter pressure reservoir for containing air at a pressure intermediate said first two reservoirs; a cylinder; a piston in said cylinder; a stamp head connected to said piston; connections between said first named reservoir and the 125 130

- top of said cylinder; connections between the bottom of said cylinder and said third named reservoir; exhaust connections between the top of said piston and said second 5 named reservoir; a compressor; connections between the suction end of said compressor and said second reservoir; and connections between the delivery end of said compressor and said first named reservoir, substantially 10 as described.
2. In a stamping machine the combination of a reservoir for containing air at admission pressure; a reservoir for containing air at exhaust pressure; a counter pressure 15 reservoir for containing air at a pressure intermediate said first two reservoirs; a cylinder; a piston in said cylinder; a stamp head connected to said piston; valved connections between said first named reservoir 20 and the top of said cylinder; valveless connections between the bottom of said cylinder and said third named reservoir; valved exhaust connections between the top of said piston and said second named reservoir; a 25 compressor; connections between the suction end of said compressor and said second reservoir; and connections between the delivery end of said compressor and said first named reservoir, substantially as described.
3. In a stamping machine the combination of a reservoir for containing air at admission pressure; a reservoir for containing air at exhaust pressure; a counter pressure 30 reservoir for containing air at a pressure intermediate said first two reservoirs; a valved connection between said first named and said last named reservoirs; a cylinder; 35 a piston in said cylinder; a stamp head connected to said piston; connections between said first named reservoir and the top of 40 said cylinder; a valve controlling said last named connection; a connection between said third named reservoir and the top of said valve when said cylinder is at the end 45 of its upward stroke; connections between the bottom of said piston and said third named reservoir; exhaust connections between the top of said cylinder and said second named reservoir adapted to be closed 50 by said piston at a predetermined period of its stroke; a compressor; connections between the suction end of said compressor and said second reservoir; and connections between the delivery end of said compressor and said first named reservoir, substantially 55 as described.
4. In an ore stamp the combination of a stamp head; a piston for operating said head; a cylinder in which said piston moves 60 up and down; a reservoir for supplying air under admission pressure to said cylinder on top of said piston; a reservoir for receiving the air thus supplied at exhaust pressure from said cylinder; a compressor having 65 its suction side connected to said second
- named reservoir and its delivery side connected to said first named reservoir; and a third reservoir for continuously supplying air under said piston at a pressure between those existing in said first and second named reservoirs, substantially as described. 70
5. In an ore stamp the combination of a stamp head; a piston for operating said head; a cylinder in which said piston moves up and down provided with clearance spaces 75 above and below said piston in which the air may be trapped; a reservoir for supplying air under admission pressure to said cylinder on top of said piston; a reservoir for receiving the air thus supplied at exhaust pressure from said cylinder; a compressor having its suction side connected to said second named reservoir and its delivery side connected to said first named reservoir; and a third reservoir and connections 80 constituting a closed system for continuously supplying air under said piston at a pressure between those existing in said first and second named reservoirs, substantially as described. 85
6. In an ore stamp the combination of a stamp head; a piston for operating said head; a cylinder in which said piston moves up and down provided with a space at its lower end in which air may be trapped on 90 an abnormally long down stroke of said piston; a reservoir for supplying air under admission pressure to said cylinder on top of said piston; a reservoir for receiving the air thus supplied at exhaust pressure from 95 said cylinder; a compressor having its suction side connected to said second named reservoir and its delivery side connected to said first named reservoir; a second compressor for supplying air from the atmosphere to said second named reservoir; and a third reservoir and connections constituting 100 a closed system for continuously supplying air under said piston at a pressure between those existing in said first and second named reservoirs, substantially as described. 105
7. The process of operating ore stamps which consists in supplying compressed air to a movable member at admission pressure and against a continuous counter pressure of an inclosed volume of air; exhausting said first named air to a compressor at a pressure less than said counter pressure; and compressing said exhausted air to admission pressure again, and resupplying the same to said movable member, substantially 110 as described.
8. The process of operating ore stamps which consists in providing a confined volume of air under pressure for continuously acting on the under side of the stamp piston; causing a confined volume of air at a higher pressure to intermittently act on the top side of said piston; exhausting the air thus admitted to the top of said piston at a 115
- 120
- 125
- 130

pressure lower than said first named air to the suction side of a compressor; and recompressing said exhausted air to its initial pressure and returning the same to the top 5 side of said piston, substantially as described.

In testimony whereof I affix my signature, in presence of two witnesses.
